UNITED STATES PATENT OFFICE

GARTH G. GILPIN, OF RIVERSIDE, ILLINOIS, ASSIGNOR TO P. H. MURPHY COMPANY, OF NEW KENSINGTON, PENNSYLVANIA, A CORPORATION OF PENNSYLVANIA

CAR ROOF

Application filed April 6, 1931. Serial No. 527,983.

This invention relates to the type of metal car roof known as the neutral axis type, wherein the roof sheets are adapted, arranged and joined together to form a roof consisting of a series of ribs alternating with channels, and the roof as a whole functions mechanically after the manner of a beam. The principal object of the present invention is to strengthen and stiffen the seam construction and adapt it for better cooperation with the body portions of the sheets in taking care of beam stresses. Another object is to secure an equal distribution of the metal above and below the geometrical center line of the roof, thereby placing the neutral axis of the roof along said line and thus enabling the maximum strength of the metal to be obtained. Another object is to avoid extending the fastening devices from the outside to the inside of the car. Another object is to utilize the space between the upper and lower levels of the roof sheets to accommodate the roof seams wholly or in part.

The invention consists in the parts and in the arrangements and combinations of parts hereinafter described.

In the accompanying drawing, which forms part of this specification and wherein like reference letters and numerals refer to like parts wherever they occur,

Fig. 1 is a plan view of a portion of a car roof embodying my invention,

Fig. 2 is a vertical transverse cross-section through one-half of the roof on the line 2—2 in Fig. 1,

Fig. 3 is a vertical longitudinal cross-section through the roof on the line 3—3 in Fig. 1,

Fig. 4 is an enlarged cross-section of one of the vertical seams that connect the margins of adjacent sheets,

Figs. 5 and 6 are cross-sectional views similar to Fig. 4, showing seams of modified form.

Conformably to the so-called neutral axis type of roof, the roof sheets 1 of the present invention form a series of flat-topped ribs A at one level alternating with a series of flat-bottomed channels B of substantially equal cross-sectional area at a lower level, said

sheets extending from side plate to side plate 2 of the car and the ribs A merging at or near the ends of the sheets into the plane of the bottoms of the channels B.

According to the present invention the longitudinal middle portion of each sheet is offset upwardly with respect to the marginal portions thus forming a rib A, such middle portion and the marginal portions being integrally connected throughout their length by upstanding web members 3 that decrease in height from a maximum at the ridge to a point at or near the eaves where they merge into the plane of the side portions. Along each side margin of the sheet is an upstanding flange 4. The sheets are arranged side by side with their ends riveted to the side plates 2 and with seam caps 5 straddling the upstanding flanges 4 of adjacent sheets and rigidly secured thereto, preferably along the neutral axis of the roof.

Preferably the seam cap 5 is a strip of metal of heavier gage than the sheets, which strip is folded on itself and provided along its longitudinal edges with flanges 6 that rest on the body portions of adjacent sheets. By this arrangement, the seams are located at the middle of the channels B; and as the rivets 7 extend horizontally through the seam caps 5 and sheet flanges 4, they are wholly outside of the car where they are easy to drive and where they produce no danger of leakage into the car. As the seams are located in the channels B, they need not project at the ridge of the car above the upper level of the roof sheets; and even in the region of the eaves, such seams can be kept low enough to keep inside the lines established for clearance of tunnels and bridges.

One of the advantages of the present car is that the entire seam construction, including the sheet flanges and seam cover, cooperate efficiently with the middle of the sheets in taking care of the stresses on the roof, especially as the metal in the roof is so distributed that the neutral axis of the roof as a whole is approximately midway between the upper and lower levels of the roof sheets and especially also because the seam construction is relatively only a short distance 100

from the vertically disposed sides of the channels, which sides function as the web members of the roof structure considered as a beam. By reason of the relatively short 5 distance between said web members and the seam construction, the resistance to buckling stresses is greatly increased and there is more efficient cooperation in taking care of mechanical stresses.

- 10 In order to place the neutral axis midway between the upper and lower panels of the roof, it is preferable to make the width of the upper middle panel of the sheet substantially equal to the combined widths of the two lower 15 side panels thereof, and to make said side portions equal to each other, especially as this locates the seam at the middle of the channel.

The roof sheet hereinbefore described has 20 the advantage that it may be readily made of galvanized metal without injuring the same, and that it is easy to apply to the car. Obviously the design of the seam cover admits of considerable variation both as to the thickness 25 of the material and the cross-sectional shape thereof; and the seam construction may be varied or strengthened by reinforcing strips of metal interposed between the roof sheets. For instance, in the modification 30 illustrated in Fig. 5, the reinforcing strip is a flat strip 8 interposed between the sheet flanges, while in the construction illustrated in Fig. 6, the reinforcing strip 9 is of inverted channel shape.

35 What I claim is:

1. A car roof comprising roof sheets having upstanding flanges along their side margins rigidly secured together, each sheet having its longitudinal middle portion at one 40 level and its side portions at a different level, the cross-sectional area of the middle portion of a sheet being substantially equal to the cross-sectional area of the two side portions thereof.

45 2. A metal car roof having alternating flat-topped ribs and flat-bottomed channels formed therein extending crosswise of the car, said roof consisting of a plurality of roof sheets that have their adjacent margins connected by upstanding seams that extend longitudinally of said channels substantially midway of the sides thereof, the cross-sectional area of said ribs, said channels and said seams being such that the amount of metal above 50 the neutral axis of the roof is substantially equal to the amount of metal below such neutral axis.

60 3. A metal car roof having alternating flat-topped ribs and flat-bottomed channels formed therein extending crosswise of the car, said roof consisting of a plurality of roof sheets that have their adjacent margins connected by vertical seams that extend longitudinally of said channels intermediate between the sides thereof, the cross-sectional 65

area of said ribs, said channels and said seams being such that the amount of metal above the neutral axis of the roof is substantially equal to the amount of metal below such neutral axis.

4. A car roof having alternating flat-topped ribs and flat-bottomed channels formed therein that extend crosswise of the car, said roof comprising a plurality of roof sheets secured together along their adjacent margins by hollow seams located near the middle of said channels and between the upper and lower levels of the roof. 70

5. A car roof having alternating flat-topped ribs and flat-bottomed channels formed therein that extend crosswise of the car, said roof comprising a plurality of roof sheets secured together along their adjacent margins by hollow seams located between the upper and lower levels of the roof, and stiffening members secured within said hollow seams. 75

6. A car roof whose longitudinal cross-section comprises alternating flat-topped ribs and flat-bottomed channels, said roof consisting of a plurality of roof sheets that have their adjacent margins connected together by vertical seams that extend longitudinally of said channels intermediate the sides thereof, and stiffening members secured within 80 said seams. 85

7. A car roof whose longitudinal cross-section comprises alternating flat-topped ribs and flat-bottomed channels, said roof consisting of a plurality of roof sheets that have their adjacent margins connected together by vertical seams that extend longitudinally of said channels substantially midway between the sides thereof. 100

8. A car roof whose longitudinal cross-section comprises alternating flat-topped ribs and flat-bottomed channels, said roof consisting of a plurality of roof sheets that have their adjacent margins connected together by vertical seams that extend longitudinally of said channels substantially midway between the sides thereof, said seams comprising vertical flanges along their side margins and seam caps that straddle said flanges, the cross-sectional area of 105 said ribs and said channels being substantially equal and the metal in said seam being so distributed as to place the neutral axis of the roof as a whole approximately midway between the upper and lower levels of the 110 roof. 115

9. A car roof whose longitudinal cross-section comprises alternating flat-topped ribs and flat-bottomed channels, said roof consisting of a plurality of roof sheets that have their adjacent margins connected together by vertical seams that extend longitudinally of said channels substantially midway between the sides thereof, said seams comprising vertical flanges along their side 120 125

5 margins and seam caps that straddle said flanges, the cross-sectional area of said ribs and said channels being substantially equal and the metal in said seam being so distributed as to place the neutral axis of the roof as a whole approximately midway between the upper and lower levels of the roof, said seam caps being rigidly secured to adjacent seam flanges approximately along the

10 neutral axis of the roof.

10. A car roof sheet having upstanding flanges along its side margins and having its longitudinal middle portion at one level and its side portions at a different level, the 15 cross-sectional area of the middle portion of said sheet being substantially equal to the cross-sectional area of the two side portions thereof.
